UNITED STATES PATENT OFFICE

WILLIAM C. BIDWELL AND ALBERT L. CUTLER, OF PORTLAND, OREGON

LOUD-SPEAKER APPARATUS

Application filed February 25, 1932. Serial No. 595,134.

This invention relates to improvements in loud-speaker apparatus, and has for its principal object the provision of novel and efficient apparatus associated with the loud-speaker mechanism for modulating the emitted amplified sound vibrations to maintain the true pitch and natural reproduction of the original tones throughout the entire sound register audible to the ear.

10 A further object of the invention is to provide sound-modifying apparatus of simple and practicable construction including a sound-board to which the speaker-cone is connected, and a tone-box arranged interiorly and in intimate contact with the sound-board, such apparatus in its assembly and combination affording a marked betterment in the quality and fidelity of tone produced by loud-speakers and admitting of greatly 20 amplified volume without distortion from the original sound impulses.

A still further object of the invention consists in the provision of a sound-board in conjunction with a loud-speaker and particularly in the especial form thereof embodied in the present disclosure whereby a board of relatively large size and capacity may be employed without unduly increasing the size of the loud-speaker apparatus.

30 Other objects and advantages residing in our invention, and objects relating to details of construction and arrangements of parts thereof, will be readily apparent in the course of the following detailed description.

35 The accompanying drawing illustrates by way of example a representative form of our invention, in which:

Figure 1 is a perspective view of loud-speaker apparatus embodying our invention, shown mounted in a supporting frame.

40 Fig. 2 is a view in longitudinal vertical section, being shown upon an enlarged scale and removed from the supporting frame.

45 Fig. 3 is a view in front elevation with the horn removed.

Fig. 4 is a view in vertical section on line 4-4 of Fig. 2.

50 Referring to said views, the reference numeral 1 indicates the base-board of our improved sound modulating apparatus for

loud-speakers. Said base-board is formed of wood of approved resonant qualities and is desirably rectangular in configuration with its opposite sides in parallel planes. It is provided with an axially disposed circular 55 aperture 2 about whose periphery on its inner side the flange 3 of a loud-speaker cone 4 is secured in the usual manner with a cushion gasket 5 interposed therebetween. The loud-speaker apparatus is shown at 6 extending 60 rearwardly from the speaker-cone.

Secured to the perimeter of the base-board 1 in tightly doweled and cemented condition so as to be for the purposes of sound-vibration homogeneous is an extension disposed in right-angled relation thereto and consisting of top and bottom walls 7 and 8 and opposite side walls 10. The base-board joins the rectangular extension on a line spaced inwardly from the forward edge of the extension to provide 70 a relatively shallow, open-front chamber 11 forwardly of the base-board.

Spaced rearwardly from the base-board 1 a partition-board 12 is joined at its outer rectangular edges to the extension-walls 7, 75 8 and 10 in parallel with the base-board and provides a chamber 13 at its rear within the overhanging walls of the extension, said chamber being open at its rearward side. Said partition is formed with a square opening 15 somewhat larger than the circular aperture 2 and disposed symmetrically with respect to the axis thereof and through which the loud-speaker apparatus 6 may project if desired.

80 Liner-boards 16 are rigidly secured in rectangular relation and parallel, respectively, to the extension-walls 7, 8 and 10, between the base-board 1 and the partition 12 laterally enclosing the speaker-chamber 17 and forming exteriorly thereof the tone-box 18 extending uninterruptedly entirely about the interior of the extension-walls and the outer portion of the base-board. Said tone-box is entirely enclosed excepting for a plurality of 90 apertures 20 formed in the base-board and spaced symmetrically about the central aperture 2.

95 A horn 21 is secured at its small end to the exterior surface of the base-board about the 100

opening 2 and extends flaringly to beyond the limits of the forward chamber 11. At the rear of the apparatus and spaced from the rear edges of the extension-walls is a reflector-disc of substantially concavo-convex form and within whose concavity the rear edges of the extension walls may extend. Said reflector-disc may be formed of any suitable highly reverberatory material and is supported upon wooden arms 22 secured in the angles of the liners 16 and projecting rearwardly of the chamber 13.

The apparatus may be mounted in any desired manner but advantageously may be supported within a skeleton metal frame 23 being suspended therein by flexible or elastic straps 25, whereby the apparatus is in a manner insulated from exterior causes and its acoustical properties thereby unaffected.

It will be noted that the base-board 1 and extension-walls 7, 8 and 10 are practically homogeneous and integral and form collectively a sound-board of extended area in relatively small compass. The tone-box 18 of which the sound-board forms two walls serves to modulate and control the vibratory action of the sound-board and maintain the sound-waves issuing therefrom in faithful reproduction of the original tones and to reproduce the sound impulses of vibratory frequencies at their true pitch regardless of the volume at which the sound-waves may be amplified.

Additional tonal and sustaining qualities are provided through the utilization of the reflector-disc 26 which is so disposed as to reverberate forwardly practically all of the sound-waves ordinarily directed to the rear and projecting them with directional effect in parallel with the sound-waves emitted by the horn and thus avoiding adverse acoustical effects from echoes issuing from a wall or other surface located at the rear of the apparatus. Thus such rearwardly directed sound-waves are reflected forwardly and strike the ear of the auditor at substantially the same interval of time as those issuing from the horn.

Having described our invention, what we claim, is:—

1. Loud-speaker apparatus, consisting of a base-board of rectangular configuration, extensions to said base-board directed in right-angled relation from the respective edges thereof, a loud-speaker secured to said base-board about its approximate center axis, and walls directed from said base-board and extension, respectively, enclosing a tone-box surrounding said loud-speaker.

2. Loud-speaker apparatus, consisting of a base-board formed with an opening, a loud-speaker mounted about said opening in the base-board, an extension to said base-board extending at approximate right angles to the base-board, and a tone-box disposed within

the angle formed by said base-board and extension and surrounding said loud-speaker.

3. Loud-speaker apparatus, consisting of a base-board formed with a central opening and a plurality of smaller apertures thereabout, a loud-speaker having its cone secured about said opening in the base-board, an extension to said base-board extending at approximately at right angles to the base-board, and a tone-box disposed within the angle formed by said base-board and extension to whose chamber said apertures of the base-board communicate.

4. Loud-speaker apparatus, consisting in a sound-board having a relatively vertical base-board of rectangular configuration and extensions extending in right angled relation thereto from its respective edges, said base-board having an opening therein and a plurality of smaller apertures spaced radially therefrom, a loud-speaker having its cone secured about said opening, a tone-box disposed within the angle formed by said base-board and extensions, and a reflector-disc mounted rearwardly of said extension and spaced therefrom.

5. Loud-speaker apparatus, consisting in a base-board formed with a central opening, extensions to the periphery of said base-board extending at right-angles thereto, a tone-box disposed within the angles formed by said base-board and extensions and forming a central space within which the loud-speaker is positioned, and said speaker secured to said base-board with its cone secured about said opening.

6. Loud-speaker apparatus, consisting in a base-board formed with a central opening, extensions to the periphery of said base-board extending at right-angles thereto, a tone-box disposed within the angles formed by said base-board and extensions and providing a central space within which the loud-speaker is positioned, said speaker secured to said base-board with its cone secured about said opening, and a reflector-disc secured in spaced relation at the rear of said extensions.

7. In loud-speaker apparatus, a sound-board device consisting of a base-board, an extension therefor extending at approximately right-angles to the base-board, said extension extending at both front and rear of the base-board to provide chambered portions upon opposite sides of the base-board, and a tone-box disposed in the rear of said chamber and in the angle formed by said base-board and extension.

8. In loud-speaker apparatus, a sound-board device consisting of a base-board having an opening therein, a loud-speaker having its sound-cone secured to said base-board about the perimeter of said opening, a tone-box mounted on said base-board and having sound-apertures extending through the base-

board, and a horn extending forwardly from said opening in the base-board.

9. In loud-speaker apparatus, a sound-board consisting of a base-board having an opening therein, a loud-speaker having its sound-cone secured to said base-board about the perimeter of said opening, said base-board having an extension from its edges extending forwardly and rearwardly at approximately 5 right-angles thereto, a tone-box formed in the angle between said base-board and its rear extension, a horn extending forwardly from said opening in the base-board, and a reflector-disc rigidly mounted in spaced relation 10 to the rear of said rearwardly directed extension.

10. In loud-speaker apparatus, a sound-board consisting of a base-board having an opening therein, a loud-speaker having its sound-cone secured to said base-board about the perimeter of said opening, said base-board having an extension from its edges extending forwardly and rearwardly at approximately 20 right-angles thereto, a tone-box formed in the angle between said base-board and its rear extension, and a horn extending forwardly from said opening in the base-board.

11. In loud-speaker apparatus, a base-board having a central aperture, a rearwardly 25 extending extension from said base-board directed at approximately right angles thereto, a loud-speaker having its sound cone secured to said base-board about the perimeter of said opening, and a reflector-disk mounted 30 in spaced relation to the rear of said rearwardly directed extension.

12. In loud-speaker apparatus, a base-board having a central aperture, a rearwardly 35 extending extension from said base-board directed at approximately right angles thereto, a loud-speaker having its sound-cone secured to said base-board about the perimeter of said opening, and a reflector-disk mounted 40 in spaced relation to the rear of the rearwardly directed extension and having its 45 perimeter extending outwardly of said extension.
